COMBINED SCARF AND PRAYER SHAWL

Maurice M. Rubens, Chicago, Ill.

Application March 8, 1935, Serial No. 9,953

1 Claim. (Cl. 2—91)

The invention relates generally to a scarf, and more particularly to a scarf having associated with it certain prescribed features to make it adaptable for use as a prayer shawl.

- 5 To comply with the Mosaic law, the Hebrew prayer shawl must be provided at each of its four corners with a fringe arranged in a certain prescribed manner and formed with a prescribed number of especially arranged knots or ties.
- 10 In addition to these specially constructed fringes the shawl is also sometimes provided with a specially constructed neckband upon which appears an inscription in Hebrew, which inscription is woven in either gold, silver or white in the neck band, the latter, however, being stitched to the upper edge of the shawl intermediate the ends thereof.

The shawl also includes suitably decorated corner pieces which are attached at each corner of the shawl, said corner pieces being formed with a central opening which coincides with a similar opening formed in the body of the shawl and from which opening the corner fringe extends. The Hebrew prayer shawl is also usually provided with a plurality of black or blue stripes arranged transversely adjacent the ends of the shawl. This prayer shawl is used by men, and boys after their confirmation.

It is an object of this invention to produce a scarf which may be worn the same as any ordinary scarf and presenting substantially the same appearance, but which will have associated with it the prescribed corner fringe and other features necessary for its use as a prayer shawl, thereby making it readily convertible into a prayer shawl whenever found necessary or desirable.

Thus when so constructed, my improved scarf when folded with the neck band and corner pieces disposed on the inside, the scarf will present the same appearance as the ordinary scarf, but when folded the other way it will be suitable for use as a prayer shawl in complete compliance with the Mosaic law.

Another object of the invention is to provide a combined scarf and prayer shawl wherein the features necessary in its construction in order to comply with the Mosaic law, will, upon the folding of the scarf, be concealed from view, thereby presenting the appearance of the ordinary and well known scarf.

With the foregoing and other objects in view which will appear as the description proceeds, the invention consists in certain novel features of construction, arrangement and combination of parts hereinafter fully described, and illustrated in the accompanying drawing, and particularly pointed out in the appended claim, it being understood that various changes in the form, proportion, size and minor details of the structure may be made without departing from the spirit or sacrificing any of the advantages of the invention.

For the purpose of facilitating and understanding of my invention, I have illustrated in the accompanying drawing, a preferred embodiment thereof, from an inspection of which when considered in connection with the following description, my invention, its mode of construction, assembly and operation, and many of its advantages should be readily understood and appreciated.

Referring to the drawing in which the same characters of reference are employed to indicate corresponding or similar parts throughout the several figures of the drawing:

Fig. 2 is a plan view of the opposite side of said scarf;

Fig. 3 is an enlarged plan view of one of the corner pieces associated with my scarf; and

Fig. 4 is a view in perspective showing the same in folded position and as it would appear when worn as an ordinary scarf.

Referring to the drawing more specifically by characters of reference, the numeral 10 designates generally a scarf woven of any suitable material such as wool or silk, in white, which scarf is of a length and width commonly used for articles of this character. The scarf 10 is of generally rectangular formation and may be provided at its ends with the usual fringe 11. As so far described, the scarf is of the same general construction as the well known scarfs now appearing on the market.

In the embodiment illustrated, however, there is provided in the scarf construction certain features which are prescribed by the Mosaic law in order to make the same suitable for use as a prayer shawl. To this end, the shawl is provided at each corner thereof with a suitably ornamented or decorated corner piece of silk or wool which is stitched to the body of the shawl, said corner piece being substantially of square formation about two inches on the side and is generally designated by the reference character 12. The ornamentation usually consists of a plurality of six pointed stars woven into the fabric.

Each of said corner pieces is secured along three sides to one face of the scarf, which face is designated as the inside face. A suitable hole 13 is provided at or about the center of the corner piece, said hole co-inciding with a similar opening provided in the body of the scarf. Secured in said hole 13 is a fringe or tassel 14, which fringe must be formed of threads of white wool. In said fringe 14 are provided a plurality 10 of knots 15, said knots being of the prescribed formation and number and thus secure the fringe 14 in place in the shawl. This construction is the same for all four corners as each of said corners is provided with the corner piece 12 and 15 fringe 14.

In addition to the prescribed corner fringe 14, the shawl is also provided on the inside thereof with the neckband 16 which may also be woven of wool or silk in white and upon which is 20 inscribed a prescribed inscription in Hebrew characters, said characters may be woven in gold, silver or plain white. The body of the scarf has also provided thereon adjacent its ends a plurality 25 of transverse stripes 17, which stripes are either in black or blue, these being also required by the Mosaic law.

This completes the construction of my combined scarf and prayer shawl and when folded longitudinally with the corner pieces and neck- 30 band on the inside, the scarf may be worn in the ordinary manner and will completely conceal the decorated corner pieces and neckband, thus presenting the appearance of the usual scarf. However, when it is desired to use the same as a 35 prayer shawl, the scarf is placed around the neck with the ends thereof hanging from the shoulders, and when used in this manner, the neckband and decorated corner pieces are on the outside, the appearance thus presented being 40 of the regulation prayer shawl.

It will thus be noted that I have combined in a single article a scarf and a prayer shawl which will be both attractive and suitable for both purposes and which may be readily changed from one to the other of its uses.

By reason of the corner pieces 12 being secured at three sides only there is formed a pocket 18 at each corner, within which pocket may be disposed 5 the corner fringe 14 when it is desired to wear the scarf as an ordinary scarf. When it is desired to use the same as a prayer shawl, the corner fringes may be removed from their respective pockets and thus make the scarf suitable 10 for use in that manner.

It is believed that my invention, its mode of construction, and assembly, and many of its advantages should be readily understood from the foregoing without further description, and it 15 should also be manifest that while a preferred embodiment of the invention has been shown and described for illustrative purposes, the structural details are nevertheless capable of wide variation within the purview of my invention as de- 20 fined in the appended claim.

What I claim and desire to secure by Letters Patent of the United States is:

As a new article of manufacture, a scarf having a neck band secured thereto adjacent one 25 longitudinal edge thereof, a corner piece secured at each corner of said scarf and a fringe extending from each of said corner pieces, said neck band, corner pieces and fringe being of regulation construction described by Mosaic law, whereby the 30 said scarf may be used as a prayer shawl, said neck band, and corner pieces being disposed on one side of said scarf only whereby the said scarf may be worn so as to permit concealment of said neck band, corner pieces and fringe when it is 35 desired to use the same as an ordinary scarf, each of said corner pieces having one edge thereof left unsecured to form with the body of the scarf a pocket within which its associated fringe may be disposed and concealed from view when 40 the scarf is not used as a prayer shawl, said fringe being inserted into said pocket through the unsecured open edge thereof.
